Inventor:
Ernest Buz

UNITED STATES PATENT OFFICE.

ERNST BUZ, OF SONNEBERG, GERMANY.

FOLDING WALKING STICK OR SIMILAR OBJECT USABLE AS A SEAT.

Application filed November 17, 1926, Serial No. 148,972, and in Germany November 21, 1925.

This invention relates to a folding walking stick, umbrella stick and the like which can be used as a seat.

Walking sticks, so called walking staffs which can be screwed together in order to form a seat have become known. This temporary seat is formed in such a manner that the top part of the walking stick is put in a horizontal hole at the upper end of the other part of the stick. This cross hole however seriously affects the strength and durability of the respective parts of the stick and in order to avoid this inconvenience this part has been broadened in its length. By this arrangement the stick gets a bad appearance so that its use as an ordinary walking stick is usually out of question.

This inconvenience is avoided according to this invention by using a stick consisting of several parts, a connecting piece being used of which one end is formed as a sleeve preferably fitted with threads and the other end of which is formed with a spring in the shape of a lyre. This connecting piece is fixed in a convenient manner in the upper end of the bottom part of the walking stick, after the same has been taken to pieces, and in order to form a seat the upper part of the stick will be pushed between the two parts of the spring.

The walking stick according to the invention differs from known walking sticks from which can be formed a seat by the use of the special connecting piece and by the manner in which a seat is formed.

The walking stick has the appearance of an ordinary stick.

In the accompanying drawing a walking stick according to the invention is shown by way of example.

Fig. 1 shows an ordinary walking stick put together.

Fig. 2 shows the same stick arranged as a seat by the use of the connecting piece.

Fig. 3 shows the connecting piece on a larger scale in side-view.

The walking stick consists of two parts *a* and *b* screwed together by the threaded sleeve *c* and the threaded part *d*. In case that suitable material is used such as steel,

the parts *a* and *b* can directly be screwed together and the parts *c* and *d* are not required. In order to form a seat from the stick, the upper part *a* is screwed from the lower part *b* and on the upper end of this lower part, a special connecting piece *e* (Fig. 3) is screwed. The upper end of this connecting piece has the form of a lyre and between the two parts *f* the upper part *a* will be pushed, and held in this position by the spring action of these two parts *f*. In order to avoid the possibility of losing the connecting piece *e* it can be fixed on the handle of the stick by means of a small chain *g* or in a convenient manner.

I claim:—

1. In a folding walking stick, umbrella stick, or the like, the combination of a lower section provided with an externally threaded stud, a handle section provided with an internally threaded sleeve adapted to be screwed onto said stud, a connecting piece comprising an internally threaded member adapted to be screwed to the stud of the lower section of the stick after the stick has been taken to pieces in order to form a seat, this connecting piece being provided at the upper end with a lyre-shaped spring between the parts of which the upper part of the stick is pushed and held in this position by the spring.

2. In a folding walking stick, umbrella stick, or the like, the combination of a lower section provided with an externally threaded stud, a handle section provided with an internally threaded sleeve adapted to be screwed onto said stud, a connecting piece comprising an internally threaded member adapted to be screwed to the stud of the lower section after this stick has been taken to pieces in order to form a seat, this connecting piece being provided at the upper end with a lyre-shaped spring between the parts of which the upper part of the stick is pushed and held in this position by the spring, a small chain fixed on the connecting piece and on the handle being provided in order to avoid losing the connecting piece.

In testimony whereof I affix my signature.

ERNST BUZ.
